UNITED STATES PATENT OFFICE

2,002,456

METHOD OF AND APPARATUS FOR
MAKING A CANHarry Sebell, Boston, Mass., assignor of one-half
to Arthur H. Parker, Lexington, Mass.

Application May 3, 1933, Serial No. 669,127

15 Claims. (Cl. 113—7)

This invention relates to cans of the type which have a body portion and a seamless neck or cover-receiving portion secured to the body portion with a double lock seam and adapted to receive 5 a cover or closure of the plug type.

One of the objects of the invention is to provide an improved method of making a can of this type and also an improved apparatus by which such a can can be manufactured.

10 In order to give an understanding of the invention I have illustrated in the drawings a selected embodiment thereof which will now be described after which the novel features will be pointed out in the appended claims.

15 Fig. 1 is a sectional view of the seamless neck or cover-receiving portion of a can embodying my invention before it is attached to the can;

Fig. 2 is a fragmentary sectional view of the body portion of the can illustrating such body 20 portion before it has the neck portion connected thereto;

Fig. 3 is a view showing the assembled neck portion and body portion and illustrating the first step of securing said portions together with 25 the double lock seam;

Fig. 4 is a view similar to Fig. 3 showing the double lock seam completed;

Fig. 5 is a fragmentary sectional view of the completed can showing the cover or closure inserted in the mouth of the can;

Fig. 6 is a fragmentary section on the line 6—6, Fig. 3;

Fig. 7 is a fragmentary sectional view on the line 7—7, Fig. 4;

Fig. 8 is a section on the line 8—8, Fig. 6.

A can made in accordance with my invention is indicated generally at 1 and it is formed with the body portion 2 and with the neck or cover-receiving portion 4 which is secured to the upper edge 40 of the body portion 2 by means of a double lock seam indicated generally at 5.

The body portion 2 may be made with the usual side seam 3 or it may be made without the side seam.

45 One of the characteristic features of the can embodying my invention is that the neck portion forms an extension of the body portion and adds to the capacity of the can.

In the illustrated embodiment of the invention 50 the lower end of the wall of the neck portion 4 where it is joined to the body portion 2 is in alignment with the wall of the body portion 2 and forms a continuation thereof. If, therefore, the can has a cylindrical body 2 then the lower 55 end of the neck portion 4 will have a cylindrical

shape and will also have the same diameter as that of the body portion 2.

The upper edge of the neck portion 4 may be finished in any usual way and as herein illustrated it is rolled or curled outwardly to form 5 the bead 10 and where the upper end of the neck portion is treated in this manner said neck portion will have the same diameter throughout its vertical dimension as the body portion 2. A can having the neck portion of uniform diametrical 10 dimension will be free from any interior shoulders or ledges which interfere in any way with the pouring out of the contents of the can when it is opened.

In Fig. 5, which shows a fragmentary section 15 of the can, 6 indicates the cover or closure of the can, said cover being illustrated as of the so-called "plug" type, it having the upstanding curb 7 which fits tightly within the seamless neck 4. The fact that the neck 4 is seamless provides a can 20 construction in which a tight non-leaking joint will be formed between the curb 7 of the cover and the walls of the neck when the cover is in place.

So far as I am aware prior to my invention all 25 cans made with a body portion and a seamless neck or cover-receiving portion connected to the body portion with a double lock seam have been made with a neck or cover-receiving portion which extends inwardly from the upper edge of 30 the body portion and which is provided with a cover-receiving opening of less diameter than that of the can. In such a can the neck or cover-receiving portion provides an inwardly-projecting shoulder or pocket which prevents the draining 35 of the contents of the can when the latter is emptied and it also results in a can having a restricted open end as compared with the full diameter of the can.

Cans of this type are used largely for the 40 packaging of paint or similar liquid product.

In using paint from a paint can it is an advantage to have the opening in the end of the can as large as possible when the cover is removed 45 so as not to interfere with the dipping of brushes in the can. It is also an advantage to have a can which is free from any interior shoulders or portions which will prevent completely emptying the can. The can embodying my invention as described above has these desirable characteristics for when the can is open the open end is of the full diameter of the can body and the interior of the can presents no shoulders which will prevent completely draining the contents of 50 the can when the can is emptied.

55

In making the can herein shown I first provide the can body portion 2, which may or may not have a side seam 3, and which has at its upper end an outwardly-extending seaming flange 8. 5 I also provide the seamless neck or cover-receiving portion 4, the lower end at least of which has the same size as that of the body portion 2 and which is provided at its lower end with an outwardly-extending seaming flange 9 adapted to rest on 10 and mate with the seaming flange 8 of the body portion.

The upper edge of the neck portion 2 may be completed in any desirable way and as herein 15 illustrated it is curled outwardly to form the bead 10.

The body portion 2 and the neck portion 4 are connected by first assembling them with the flanges 8 and 9 in mating relation and with the wall of the neck portion in alignment with the 20 wall of the body portion as shown in Fig. 3 and said flanges are then rolled together in usual manner to form the double lock seam 5. This curling or rolling of the mating flanges 8 and 9 to form the double lock seam 5 is accomplished 25 through the medium of a chuck 11 and a seaming roll or wheel indicated at 12. The seaming chuck 11 is of a size to fit the upper end of the wall of the body portion and the lower end of the wall of the neck portion and said chuck is 30 placed within the can body and neck so as to form a backing for the wall and the neck on either side of the seam. If the neck portion 4 is of uniform diameter throughout its vertical dimension and is finished by having its upper edge rolled out- 35 wardly to form the exterior bead 10 then the seaming chuck 11 may be inserted into position through the open end of the can, in which case it will extend through the neck portion and partially into the body portion as shown in Figs. 40 3 and 4.

If the neck portion 4 is to be seamed to the body portion 2 before the bottom is attached to the can then it would be possible to insert the seaming chuck upwardly through the bottom of 45 the can into a position where it forms the backing for the upper end of the wall of the body portion and the lower end of the neck portion.

The seaming roll 12 is formed with a curling groove 16 and with a flange portion 15 above 50 the groove adapted to rest on the seaming flange 9. The seaming operation is performed by rolling the seaming roll 12 around the can to cause the curling groove 16 to act on the edges of the mating flanges 8 and 9 while the walls of the 55 body portion and the neck portion are backed by the seaming chuck 11. This operation serves to roll the flanges into the form of the double lock seam 5. This rolling of the seaming roll 12 around the can may be provided for by rotating the can about its axis or by holding the can stationary and rolling the seaming roll 12 around the can.

As herein shown the can 1 is supported on a table 13 and if the seaming operation is to be performed by rotating the can then said table 65 will be carried on a rotary shaft 30 and the seaming chuck 11 will be carried by an axially-aligned rotary shaft 31. The seaming roll 12 is shown as carried by a rotary shaft or spindle 14. It will be understood, of course, that if the shafts 30 and 31 are rotatable the power for rotating the 70 shafts may be applied to either or both of them as desired.

During the seaming operation the seaming wheel 12 is forced toward the can so as to bring 75 the bottom of the groove 16 against the flanges

8 and 9 with considerable pressure and as the can and sealing wheel rotate the pressure which is thus applied to the flanges 8 and 9 will roll them up to form the double lock seam 5, as is well understood by those familiar with can making operations. During this seaming operation the seaming chuck 11 not only forms a backing member for the body portion and the neck portion of the can but it also serves to center the neck portion with reference to the body portion 10 and hold them in their co-axial relation while the seam is being formed.

The seaming chuck 11 herein illustrated is provided with a flange 17 which overlies the upper edge 10 of the neck member and which applies sufficient pressure to the neck member to hold the seaming flanges 8 and 9 firmly in engagement during the seaming operation.

The flange 15 of the seaming or curling wheel 12 holds the flange 9 of the neck portion in its 20 proper position while the two flanges are being rolled together and thereby prevents the flange 9 from buckling upwardly during the seaming operation. At the beginning of the seaming operation the seaming roll is spaced from the can body as shown in Fig. 3 but as the seaming operation proceeds the seaming roll 12 is moved toward the can body until by the time the two mating flanges 8 and 9 have been rolled into the form of the double lock seam 5, the seaming wheel has 30 been brought into a position so that the portion 18 thereof directly below the groove 16 is in substantial contact with the outside of the can body.

In order that the flange 15 of the seaming wheel 35 may function properly it is necessary that it should overlie the seaming flange 9 of the neck portion 4 and to prevent this flange 15 from interfering with the inward movement of the seaming wheel 12 during the seaming operation I propose to make said flange 15 contractible and expandable. For this purpose said flange 15 is constituted by a plurality of flange sections 19, each being sector shaped and each being capable of movement in a radial direction.

The body of the seaming wheel 12 is made with a radial surface 20 on which the flange sections 19 rest and said sections are retained in position by a retaining ring 21 which overlies the flange sections and is secured to the body of the seaming roll through suitable rivets 22. Each flange section is of a size to permit it to move radially between the surface 20 and the retaining ring 21.

Each flange section 19 is backed by a spring 23 which normally holds it in its outward position as shown in Figs. 6 and 8 and each flange section is shown as guided in its radial movement by two of the rivets 22, there being two such rivets for each flange section and each pair of rivets extending through a slot 24 with which 55 the corresponding flange section is provided.

During the initial seaming operation the seaming wheel 12 will have the position relative to the can shown in Fig. 3 and the flange sections 19 will be extended to their full extent which is 65 sufficient to overlie the seaming flange 9 of the neck portion 4. As the forming of the double lock seam 5 progresses and the seaming wheel moves inwardly toward the can body the flange sections 19 will be brought against the neck portion and as this occurs each flange section will yield inwardly while in engagement with the neck portion. Thus the full pressure of the seaming wheel may be applied to the mating flanges 8 and 9 to roll them together thereby to form the 70 75

double lock seam 5 and the seaming flange 9 of the neck portion will at all times have a downward pressure applied thereto through the sections 19 of the expandible and contractible seam-
5 ing wheel flange 15.

I claim:

1. An apparatus for making cans having a body portion and a neck portion of the same interior diameter and which are connected by a double lock seam formed by rolling together seaming flanges on the body portion and neck respectively, said apparatus comprising means for supporting the body portion of the can, a seaming chuck for insertion into the aligned neck portion

10 and body portion to hold them in alignment and with their seaming flanges in mating relation, a seaming roll having a peripheral curling groove to act on both flanges simultaneously and roll them into the double lock seam, said seaming roll
15 also having a contractible flange adapted to engage the upper face of the seaming flange of the neck portion during the seam-forming operation.

2. An apparatus for making cans having a body portion and a neck portion which are connected by a double lock seam formed by rolling together seaming flanges on the body portion and neck respectively, said apparatus comprising means for supporting the body portion of the can, a seaming chuck for insertion into the aligned neck portion and body portion to hold them in alignment and with their seaming flanges in mating relation, a seaming roll having a peripheral curling groove to act on said flanges and roll them into the double lock seam, said seaming roll also having a contractible flange made of radially movable sections to engage the flange of the neck portion during the seam-forming operation.

3. An apparatus for making cans which have a body portion and a neck portion connected by a double lock seam formed by rolling together seaming flanges on the body portion and neck portion respectively, said apparatus comprising a seaming chuck for insertion into the aligned neck portion and body portion, a seaming roll having a peripheral curling groove to act on said flanges and roll them into a double lock seam and also having a flange portion to engage the seaming flange of the neck portion, said flange portion being formed in separate radially movable sections, and a yielding backing for each section resisting inward movement thereof.

4. An apparatus for making cans which have a body portion and a neck portion connected by a double lock seam formed by rolling together seaming flanges on the body portion and neck portion respectively, said apparatus comprising a seaming chuck for insertion into the aligned neck portion and body portion, a seaming roll having a peripheral curling groove to act on said flange and roll them into a double lock seam and also having a flange portion to engage the seaming flange of the neck portion, said flange portion being formed in separate radially movable sections, and a spring acting on each section and resisting inward movement thereof.

5. An apparatus for making cans which have a body portion and a neck portion connected by a double lock seam formed by rolling together seaming flanges on the body portion and neck portion respectively, said apparatus comprising a seaming chuck for insertion into the aligned neck portion and body portion, a seaming roll having a peripheral curling groove to act on said

flange and roll them into a double lock seam and also having a flange portion to engage the seaming flange of the neck portion, said flange portion being formed in separate radially movable sections, a spring acting on each section and resisting inward movement thereof, and means to limit outward spring-impelled movement of each section.

6. An apparatus for making cans which have a body portion and a neck portion connected by a double lock seam formed by rolling together seaming flanges on the body portion and neck portion respectively, said apparatus comprising a seaming chuck for insertion into the aligned neck portion and body portion, a seaming roll having a peripheral curling groove to act on said flange and roll them into a double lock seam and also having a flange portion to engage the seaming flange of the neck portion, said flange portion being formed in separate radially movable sections, a spring acting on each section and resisting inward movement thereof, means to limit outward spring-impelled movement of each section, and means to guide each section in its radial movement.

7. An apparatus for making cans which have a body portion and a neck portion connected by a double lock seam formed by rolling together seaming flanges on the body portion and neck portion respectively, said apparatus comprising a seaming roll having a peripheral curling groove to act on both flanges and roll them into a double lock seam and also having a contractible flange adapted to engage the upper face of the seaming flange of the neck portion during the seam-forming operation, and means engaging the interior of the body portion and neck portion and forming a backing therefor at the point where the seaming roll is acting thereon.

8. A seaming roll for rolling two mating flanges into a double lock seam, said roll having a peripheral curling groove to act on the edges of both flanges and roll them into a double lock seam and also having a contractible flange portion adapted to engage the face of one of the seaming flanges.

9. A seaming roll having a peripheral curling groove and a peripheral flange adjacent said groove, said flange being formed in separate radially movable sections, and a yielding backing for each section resisting inward movement thereof.

10. The method of making a can which consists in (1) assembling in axial alignment and with their seaming flanges in mating relation a body portion having at its upper end an outwardly-directed seaming flange and a neck portion having the same internal diameter as the upper part of the body portion and is provided with a seaming flange which mates the seaming flange of the body portion, (2) introducing into the aligned neck and body portions a seaming chuck which fits the interior of the body and neck portions, and (3) rolling the mating flanges into a double lock seam.

11. The method of making a can which consists in (1) assembling in axial alignment and with their seaming flanges in mating relation a body portion having at its upper end an outwardly-directed seaming flange and a neck portion having the same internal diameter as the upper part of the body portion and is provided with a seaming flange which makes the seaming flange of the body portion, (2) introducing into the aligned neck and body portions through the

upper end of the neck portion a seaming chuck which fits the interior of the body and neck portions, and (3) rolling the mating flanges into a double lock seam.

- 5 12. An apparatus for making a can which has a body portion and a neck portion of the same interior diameter and which are connected by a double lock seam formed by rolling together seaming flanges on the neck portion and body portion 10 respectively, said apparatus comprising means for supporting the body portion of the can, a seaming chuck fitting the interior of the neck portion and body portion and adapted for insertion into the body portion through the neck portion, said 15 chuck holding the neck portion and body portion in alignment and having means for pressing the seaming flanges together, a seaming roll having a peripheral curling groove to act on both flanges simultaneously and roll them into a double lock 20 seam, said seaming roll also having a flange extending thereabout and normally projecting beyond the curling groove, said flange of the seaming roll engaging the neck portion and being contractible progressively as the seaming 25 flanges are being rolled into the double lock seam.
13. An apparatus for making cans which have a body portion and a neck portion connected by a double lock seam formed by rolling together seaming flanges on the body portion and neck

portion respectively, said apparatus comprising a seaming roll having a peripheral curling groove to act on both flanges simultaneously and roll them into a double lock seam, and also having an outwardly-extending peripheral flange adapted to engage the upper face of the seaming flange of the neck section during the seam-forming operation, said peripheral flange being progressively contractible throughout its extent, and means engaging the interior of the body portion and neck portion and forming a backing therefor at the point where the seaming roll is acting thereon.

14. A seaming roll for rolling two mating flanges into a double lock seam, said roll having a peripheral curling groove to act on the edges of both flanges and roll them into a double lock seam and also having an annular flange portion adapted to engage the face of one of the seaming flanges, said flange portion being sectionally contractible. 15

15. A seaming roll for rolling two mating flanges into a double lock seam, said roll having a peripheral curling groove to act on the edges of both flanges and roll them into a double lock seam and also having an annular flange portion adapted to engage the face of one of the seaming flanges, said flange portion being progressively contractible throughout its extent. 20

HARRY SEBELL.
